DESIGN FOR AN ELECTROTHERAPEUTIC CABINET

Paul Meminger, Los Angeles, Calif.

Application December 1, 1944, Serial No. 116,648

Term of patent 14 years

(Cl. D26—5)

To all whom it may concern:

Be it known that I, Paul Meminger, a citizen of the Dominion of Canada, residing in the city of Los Angeles, in the county of Los Angeles and State of California, have invented a new, original, and ornamental Design for an Electrotherapeutic Cabinet, of which the following is a specification, reference being had to the accompanying drawing forming a part thereof.

Fig. 1 is a top plan view of an electrotherapeutic cabinet showing my new design,

Fig. 2 is a front elevational view of the cabinet,

Fig. 3 is an elevational view showing one end of said cabinet, and

Fig. 4 is an elevational view showing the other end of the same.

I claim:

The ornamental design for an electrotherapeutic cabinet, substantially as shown.

PAUL MEMINGER.
